UNITED STATES PATENT OFFICE.

CHARLES O. ERIKSON, OF KISSIMMEE, FLORIDA, ASSIGNOR, BY DIRECT AND MESNE ASSIGNMENTS, TO R. T. BUTLER, W. H. ARNOLD, AND W. A. GREGORY, ALL OF KISSIMMEE, FLORIDA.

AUTOMOBILE-RADIATOR.

1,200,823.

Specification of Letters Patent. Patented Oct. 10, 1916.

Application filed December 14, 1915. Serial No. 66,871.

To all whom it may concern:

Be it known that I, CHARLES O. ERIKSON, a citizen of the United States, residing at Kissimmee, in the county of Osceola, State of Florida, have invented certain new and useful Improvements in Automobile-Radiators; and I do hereby declare the following to be a full, clear, and exact description of the invention, such as will enable others skilled in the art to which it appertains to make and use the same.

This invention relates to automobile radiators.

The object of the invention is to provide a radiator of this type formed of a plurality of detachably assembled sections, whereby the radiator may be taken apart and a desired portion thereof repaired, or a new portion supplied without the employment of skilled labor and without consuming a relatively large amount of time in effecting such repair, or supplying such new part.

A further object of the invention is to provide a radiator of the character named, which, while capable of being separated with ease and facility, will possess a maximum efficiency essential to the correct operation of devices of this character.

With the above and other objects in view, the invention consists in the details of construction and in the arrangement and combination of parts to be hereinafter more fully described and particularly pointed out in the appended claims.

In describing the invention in detail, reference will be had to the accompanying drawings wherein like characters of reference denote corresponding parts in the several views, and in which—

Fig. 1 is a rear view of a radiator constructed in accordance with the invention; Fig. 2, a vertical section of the radiator; Fig. 3, a section on the line 3—3 of Fig. 2. Fig. 4, a fragment of what is shown in Fig. 2 on an enlarged scale; Fig. 5, a section on the line 5—5 of Fig. 4, and Fig. 6, a perspective view of a fragment of the circulating pipes.

Referring to the drawings, the improved radiator is shown as comprising upper and lower heads in the form of casings 10 and 11 respectively. The upper casing 10 is provided at its ends with depending arms 12 and 13, while the lower casing 11 is provided at its ends with upwardly extending

arms 14 and 15. Disposed between the ends of the arms 12 and 14 is a filler member 16, having flanges 17 overlying the outer sides of the arms 12 and 14 respectively. Likewise there is disposed between the ends of 60 the arms 13 and 15 a filler member 18, having flanges 19 which overlie the outer sides of the arms 13 and 15.

The radiator illustrated is shown as comprising four similar connections between the 65 upper and lower casings 10 and 11, but it will be noted that the number of these circulating connections between the casings can be varied, and as they are identical in structure, only one of them will be described in 70 detail, and the reference characters employed will be applied to corresponding parts of the other connections shown.

Secured within each of the arms 12 and 13 is a block 20, having a vertical opening 75 or passage 21 therein which communicates directly with the interior of the casing 10. Each block 20 is also provided at the inner end of the passage 21 with a chamber 22 and with a transverse passage 23 intersected by 80 the chamber 22. Extending through the passage 23 and through openings in the flanges 17 and 19, is a tie rod 24. This rod is tubular and has the respective ends thereof closed. Threaded on the ends of the rod 85 24 are nuts 25, which when screwed home, bind the flanges 17 and 19 to the arms 12 and 13 and, of course, afford a means for holding the filler members 16 and 18 in place.

The rod 24 is provided with a plurality of 90 openings 26, certain of which communicate directly with the chambers 22 of the blocks 20. Surrounding the rod 24 is a tubular pipe 27, the ends of which are closed by bushings 28. It will be obvious that the rod 24 and the nuts 25 serve to secure the pipe 27 in place. This pipe 27 is of a diameter somewhat greater than the diameter of the rod 24, so that a suitable water space around the rod 24 is provided. Also mounted 95 in the arms 14 and 15 of the casing 11, are blocks 29, similar to the blocks 20. Passing through these blocks 29 and through the flanges 17 and 19, is a tubular rod 30, having its ends closed and provided with 100 threads on which are engaged nuts 31. By this construction, it will be apparent that the rod 30 serves to secure the flanges 17 and 19 to the arms 14 and 15. In this way the casings 10 and 11 are suitably united. The 105

rod 30 is provided with a plurality of 110 openings 32, certain of which communicate directly with the chambers 22 of the blocks 20. The rod 30 is of a diameter somewhat greater than the diameter of the rod 24, so that a suitable water space around the rod 30 is provided. Also mounted in the arms 14 and 15 of the casing 11, are blocks 29, similar to the blocks 20. Passing through these blocks 29 and through the flanges 17 and 19, is a tubular rod 30, having its ends closed and provided with 115 threads on which are engaged nuts 31. By this construction, it will be apparent that the rod 30 serves to secure the flanges 17 and 19 to the arms 14 and 15. In this way the casings 10 and 11 are suitably united. The 116

rod 30 is also provided with a plurality of openings 32, certain of which communicate with respective chambers in the blocks 29. The rod 30 is surrounded by a pipe 33, the ends of which are closed by bushings 34. The pipe 33 is of greater diameter than the rod 30, so that a water space is formed around said rod. The pipes 27 and 33 are connected by a plurality of vertical pipes 35 and the latter are mutually connected by a plurality of radiating strips 36. The casing 10 is provided with a water inlet 37, while the casing 11 is provided with a water outlet 38. Through the medium of this inlet 10 and outlet 15 the radiator is connected with the explosive engine in the usual and well known manner. Water is adapted to be supplied to the radiator through a filling opening 39 in the casing 10, which opening is closed by a removable cap 40. An ornamental covering 41 may be provided around the radiator, and this covering is adapted to be held in place by bolts 42, which are passed through the filler members 16 and 18. 25 In operation the water will enter the casing 10, flow through the passages 21 into the chambers 22 of the blocks 20, thence through certain of the openings 26 into the interior of the rod 24, and then pass through the other openings 26 of the rod 24 into the space between said rod and the pipe 27, then through the pipes 35 into the space between the rod 30 and the pipe 33, then through certain of the openings 32 in the rod 30 into the interior of said rod, then out through certain of the openings 32 into the chambers of the blocks 29, then into the casing 11, and then to the engine to be cooled.

What is claimed is:

40 1. A radiator comprising upper and lower casing heads, having inwardly directed arms

at their ends respectively, tubular rods engaged through the arms of respective casings and provided with a plurality of openings, certain of which communicate with the interior of the related casing, said rods having their outer ends closed, nuts threaded on the outer ends of said rods and bearing against the related casing, a pipe surrounding each rod and of greater diameter than the rod, 45 bushings closing the ends of said pipes and bearing against the inner sides of the arms of the related casing, and a plurality of pipes connecting the interiors of the pipes which surround respective rods. 50

2. A radiator comprising upper and lower casing heads having inwardly directed arms at their ends respectively, blocks provided with chambers mounted in respective arms of the casing and having chambers therein 60 communicating with the interior of the related casing, tubular rods engaged through the arms and blocks of respective casings and provided with a plurality of openings, certain of which communicate with the 65 chambers of respective blocks, said rods having their outer ends closed, nuts threaded on the outer ends of said rods and bearing against the related casing, a pipe surrounding each rod and of greater diameter than the rod, bushings closing the ends of 70 said pipes and bearing against the inner sides of the arms of the related casing, and a plurality of pipes connecting the interiors of the pipes which surround respective rods. 75

In testimony whereof, I affix my signature, in the presence of two witnesses.

CHARLES O. ERIKSON.
